(57) **CLAIM**

The ornamental design for a combined snap-in wall plate and cover, as shown and described.

DESCRIPTION

FIG. 1 is a front, side perspective view of a first embodiment of a combined snap-in wall plate and cover showing the new design;

FIG. 2 is a front view of the wall plate for the combined snap-in wall plate and cover of FIG. 1;

FIG. 3 is a sectional side view of the wall plate of FIG. 2; FIG. 4 is a right side view of the wall plate of FIG. 2, the left side view being the same;

FIG. 5 is a top view of the wall plate of FIG. 2, the bottom view being the same;

FIG. 6 is a back view of the wall plate of FIG. 2;

FIG. 7 is a front view of the cover for the snap-in wall plate cover of FIG. 1;

FIG. 8 is a top view of the cover shown in FIG. 7, the bottom view being the same;

FIG. 9 is a back view of the cover of FIG. 7;

FIG. 10 is a cross-sectional view of the cover shown in FIG. 9 taken along the lines 10-10;

FIG. 11 is a right side view of the cover of FIG. 7, the left side view being the same;

FIG. 12 is a perspective view of a second embodiment of a combined snap-in wall plate and cover showing the new design;

FIG. 13 is a front view of the wall plate for the combined snap-in wall plate and cover shown in FIG. 12;

FIG. 14 is a sectional view of the wall plate shown in FIG. 13;

FIG. 15 is a right side view of the wall plate shown in FIG. 13, the left side view being the same;

FIG. 16 is a top view of the wall plate shown in FIG. 13, the bottom view being the same;

FIG. 17 is a back view of the wall plate shown in FIG. 13;

FIG. 18 is a front view of the cover for the combined snap-in wall plate and cover of FIG. 12;

FIG. 19 is a top view of the cover shown in FIG. 18, the bottom view being the same;

FIG. 20 is a back view of the cover shown in FIG. 18;

FIG. 21 is a cross-sectional view of the cover shown in FIG. 20 taken along the lines 20-20;

FIG. 22 is a right side view of the cover shown in the FIG. 18, the left side view being the same;

FIG. 23 is a front perspective view of a third embodiment of a cover for a combined snap-in wall plate and cover showing the new design;

FIG. 24 is a front view of the wall plate for the cover of the combined snap-in wall plate and cover shown in FIG. 23;

(Continued)

FIG. 25 is a right side view of the wall plate shown in FIG. 23, the left side view being the same;
 FIG. 26 is a top view of the wall plate shown in FIG. 23, the bottom view being the same;
 FIG. 27 is a back view of the wall plate shown in FIG. 23;
 FIG. 28 is a front view of the cover shown in FIG. 23;
 FIG. 29 is a top view of the cover shown in FIG. 28;
 FIG. 30 is a back view of the cover shown in FIG. 28;
 FIG. 31 is a cross-sectional view of the cover shown in FIG. 30 taken along the lines 31-31;
 FIG. 32 is a right side view of the cover shown in the FIG. 28, the left side view being the same;
 FIG. 33 is a front, side perspective view of fourth embodiment of a cover for a combined snap-in wall plate and cover showing the new design;
 FIG. 34 is a front view of a wall plate for the cover of the combined snap-in wall plate and cover shown in FIG. 33;
 FIG. 35 is a right side view of the wall plate shown in FIG. 34, the left side view being the same;
 FIG. 36 is a top view of the wall plate shown in FIG. 34, the bottom view being the same;
 FIG. 37 is a back view of the wall plate shown in FIG. 34;
 FIG. 38 is a front view of the cover shown in FIG. 33;
 FIG. 39 is a top view of the cover shown in FIG. 38, the bottom view being the same;
 FIG. 40 is a back view of the cover shown in FIG. 38;
 FIG. 41 is a cross-sectional view of the cover shown in FIG. 40, taken along the lines 41-41;
 FIG. 42 is a right side view of the cover shown in the FIG. 38, the left side view being the same;
 FIG. 43 is a front, side perspective view of a fifth embodiment of a cover for a combined snap-in wall plate and cover showing the new design;
 FIG. 44 is a front view of the wall plate for the cover of the combined snap-in wall plate and cover shown in FIG. 43;
 FIG. 45 is a right side view of the wall plate shown in FIG. 44, the left side view being the same;
 FIG. 46 is a bottom view of the wall plate shown in FIG. 44;
 FIG. 47 is a back view of the wall plate shown in FIG. 44;
 FIG. 48 is a front view of the cover shown in FIG. 43;
 FIG. 49 is a bottom view of the cover shown in FIG. 48;
 FIG. 50 is a back view of the cover shown in FIG. 48;
 FIG. 51 is a cross-sectional view of the cover shown in FIG. 50 taken along the lines 51-51;
 FIG. 52 is a right side view of the cover shown in FIG. 48, the left side view being the same;
 FIG. 53A is an exploded view of callout A in FIG. 1;
 FIG. 53B is an exploded view of callout B in FIG. 1;
 FIG. 54A is an exploded view of callout C in FIG. 5;
 FIG. 54B is an exploded view of callout D in FIG. 5;
 FIG. 55A is an exploded view of callout E in FIG. 12;
 FIG. 55B is an exploded view of callout F in FIG. 12;
 FIG. 55C is an exploded view of callout G in FIG. 12;
 FIG. 56A is an exploded view of callout H in FIG. 16;

FIG. 56B is an exploded view of callout I in FIG. 16;
 FIG. 56C is an exploded view of callout J in FIG. 16;
 FIG. 57A is an exploded view of callout K in FIG. 26;
 FIG. 57B is an exploded view of callout L in FIG. 26;
 FIG. 57C is an exploded view of callout M in FIG. 26;
 FIG. 57D is an exploded view of callout N in FIG. 26;
 FIG. 58A is an exploded view of callout O in FIG. 36;
 FIG. 58B is an exploded view of callout P in FIG. 36;
 FIG. 58C is an exploded view of callout Q in FIG. 36;
 FIG. 58D is an exploded view of callout R in FIG. 36;
 FIG. 58E is an exploded view of callout S in FIG. 36;
 FIG. 59A is an exploded view of callout T in FIG. 46;
 FIG. 59B is an exploded view of callout U in FIG. 46;
 FIG. 59C is an exploded view of callout V in FIG. 46;
 FIG. 59D is an exploded view of callout W in FIG. 46;
 FIG. 59E is an exploded view of callout X in FIG. 46; and,
 FIG. 59F is an exploded view of callout Y in FIG. 46.
